UNITED STATES PATENT OFFICE.

JONATHAN HARRIS, OF CLEVELAND, OHIO.

DESIGN FOR A FENCE-FASTENER.

SPECIFICATION forming part of Design No. 25,615, dated June 9, 1896.

Application filed March 27, 1896. Serial No. 585,134. Term of patent 14 years.

To all whom it may concern:

Be it known that I, JONATHAN HARRIS, a citizen of the United States, and a resident of Cleveland, in the county of Cuyahoga, State of Ohio, have invented and produced a new and original Design for Fence-Fasteners, of which the following is a specification, reference being had to the accompanying drawings, showing a part thereof.

10 In the drawings, Figure 1 is a side elevation. Fig. 2 is an end view, and Fig. 3 is a central longitudinal section exhibiting my design in full. Fig. 4 is a transverse section taken on a reverse section-line to Fig. 3.

15 In the figures, 1 represents a globular figure provided with circular openings 2, 3, 4, and 5, represented upon the same great arc of the circle and diametrically opposite in

pairs, as if projected by cylinders intersecting at right angles on the common plane. The 20 cylinders, however, are shown in the sections in Figs. 3 and 4 to pass around one another in the center of the globe at the intersecting point, as shown in dotted and sectional lines.

The appearance of this design is that of a 25 globe with four openings on a central plane, passing through the globe as described.

I claim, therefore—

The design for a fence-fastener herein shown and described.

JONATHAN ^{his} X HARRIS.
